UNITED STATES PATENT OFFICE.

WILLIAM BEALL GRAY, OF LOUISVILLE, KENTUCKY, ASSIGNOR TO MARTIN J. BANNON,
OF LOUISVILLE, KENTUCKY.

PIPE-SUPPORT.

1,133,855.

Specification of Letters Patent.

Patented Mar. 30, 1915.

Application filed July 15, 1914. Serial No. 851,222.

To all whom it may concern:

Be it known that I, WILLIAM B. GRAY, a citizen of the United States, and a resident of Louisville, in the county of Jefferson and 5 State of Kentucky, have invented a new and useful Improvement in Pipe-Supports, of which the following is a specification.

My invention is an improvement in pipe supports, and has for its object to provide 10 a device of the character specified, adapted to carry a certain character of pipe used in heating systems, or for other purposes wherein the pipe is subject to expansion and contraction.

15 In the drawings:—Figure 1 is a perspective view of the cradle and the supporting roller, Fig. 2 is a partial transverse vertical section, and Fig. 3 is a side view of the support with the pipe in place.

20 The present embodiment of the invention comprises a cradle consisting of a plate 1 of suitable material, having on its upper face upstanding longitudinally extending ribs 2, the said ribs having their upper 25 edges provided with rack teeth 3. The ribs are connected at their ends by transverse ribs 4, the ribs 4 being integral with the ribs 2, and each of the ribs 4 is braced against the plate 1 at each end, by integral 30 braces 5.

The ribs 2 are spaced apart inwardly from the side edges of the plate 1, and the teeth 3 extend from near one end of each rib 2 to near the other, leaving however, a 35 blank or plain space at each end at the junction of the rib with the adjacent rib 4. At each end and at each side of its under face the plate 1 is provided with a transverse finger or boss 6, for engaging pockets 40 in the supporting ribs of the conduits forming the subject-matter of my copending applications, Serial No. 723,206, filed Sept. 30, 1912, Serial No. 782,661, filed August 2, 1913, Serial No. 784,129, filed August 11, 45 1913, and Serial No. 786,110, filed August 22, 1913.

Transverse reinforcing ribs 7 are also provided, extending between the fingers at each 50 end of the plate, and connecting the said fingers, the ribs 7 extending below the lowest portions of the fingers 6, but being of less width as shown more particularly in Fig. 4. The fingers at each end of the plate 1 are in alinement, and each rib 7 is integral at its 55 ends with the adjacent fingers 6.

The pipe 8 provided with the usual insulating cover 9 is supported by a spool or roller, the said spool or roller 10 being grooved peripherally as indicated at 11 to fit the insulating covering 9 of the pipe or to fit 60 the pipe where no insulating covering is used. The spool or roller is also provided at each end with a spur gear or gear wheel 12, for engaging the adjacent series of rack teeth, and the roller is of such length that 65 it will just fit within the ribs 2, with the gears or pinions 12 in engagement with the teeth.

It will be noted from an inspection of Figs. 1 and 2, that the grooved surface 11 70 of the roller does not extend to the end of the roller, but leaves a plain surface at each end, between the groove 11 and the pinion or gear 12. The cradles are arranged in the conduits with the fingers 6 in engagement 75 with the notches or recesses in the supporting ribs of the conduit, and the engagement of the fingers with the said notches or recesses anchors the cradle in this position, against movement longitudinally of the 80 conduit, and also against twisting movement.

The ends of the spool or roller by their engagement with the inner faces of the ribs 2 prevent any shifting movement of the roller with respect to the cradle, and the 85 spur gears 12 assist in this function. As many spools or rollers are used as may be necessary to properly support the pipe, and it will be obvious that for every spool or roller a cradle is necessary.

The pinions by their engagement with the rack teeth 3 insure that the roller will not shift angularly but will hold its exact transverse position with respect to the cradle, and the engagement between the spool and 95 the cradle is such that whatever the expanding or contracting movement of the pipe, the parts will always occupy a certain definite position with respect to each other.

The bottom of the cradle plate 1 is the 100 supporting means, the plate resting on the conduit ribs and the finger bosses acting merely as anchorages and not as support and anchorage combined as in the case of my copending applications.

I claim:—

1. A pipe support, comprising a cradle consisting of a plate provided on its upper face near each side edge and near each end with an upstanding rib, said ribs being in- 110

tegral at their ends, and the side ribs having rack teeth at their upper edges, the teeth of the ribs registering, and a roller having a peripheral groove for receiving the pipe to be supported, and fitting between the side ribs, and having a pinion at each end for engaging the adjacent series of teeth, the pinions being of equal size and of less diameter than the largest diameter of the roller and co-axial with the roller to form at each end of the roller an annular shoulder for engaging the inner face of the adjacent rib to prevent longitudinal movement of the roller, said cradle having on the under face of the plate pairs of fingers, each pair of fingers being near one end of the plate and being in alinement transversely of the plate, said fingers being near the side edges of the plate and adapted to anchor the plate from movement longitudinally.

2. A pipe support comprising a cradle

consisting of a plate provided on its upper face near each side edge and near each end with an upstanding rib, said ribs being integral at their ends, and the side ribs having rack teeth at their upper edges, the teeth of the ribs registering, and a roller having a peripheral groove for receiving the pipe to be supported, and fitting between the side ribs, and having a pinion at each end for engaging the adjacent series of teeth, the pinions being of equal size and of less diameter than the largest diameter of the roller and co-axial with the roller to form at each end of the roller an annular shoulder for engaging the inner face of the adjacent rib to prevent longitudinal movement of the roller.

WILLIAM BEALL GRAY.
